UNITED STATES PATENT OFFICE.

EMILE RIMAILHO, OF PARIS, FRANCE, ASSIGNOR TO COMPAGNIE DES FORGES ET ACIERIES DE LA MARINE ET D'HOMECOURT, OF PARIS, FRANCE.

CATERPILLAR GUN-CARRIAGE.

1,332,067.

Specification of Letters Patent. Patented Feb. 24, 1920.

Application filed July 27, 1917. Serial No. 183,199.

To all whom it may concern:

Be it known that I, EMILE RIMAILHO, a citizen of the French Republic, and residing in Paris, France, 98 Rue de la Victoire, consulting engineer, have invented certain new and useful Improvements in and Relating to Caterpillar Gun-Carriages, of which the following is a complete specification.

10 This invention relates to a caterpillar gun-carriage forming a complete artillery unit so constructed as to permit of removal over all sorts of ground, thanks to its large bearing surface on the soil, both when traveling and when firing. This plant is particularly valuable on light or wet soils, where the mere support of the usual gun-carriage trails becomes absolutely insufficient. This caterpillar gun-carriage possesses a faculty of displacement and of pivoting by mechanical or electrical control, which permits of any displacement and change of aim necessitated by a change of objective. This caterpillar gun-carriage 25 consists essentially of a chassis having a longitudinal opening and provided with rollers which roll over the caterpillar chains actuated by driving wheels moved by a motor located on the caterpillar gun carriage itself or on a trailer wagon, the chains being located on the chassis, one cross bar of which forms a gun-carriage pivot for the top carriage supporting the trunnions of the cradle of the gun.

35 In the accompanying drawing, which illustrates by way of example one constructional form of the invention:

Figure 1 is a vertical longitudinal section of a caterpillar gun-carriage forming the subject-matter of the invention.

40 Fig. 2 is a cross section along 2--2 of Fig. 1.

Fig. 3 is a plan, the gun being brought into a horizontal position, a portion of the structure being broken away to show the details of construction.

Figs. 4 and 5 show that motor on a trailer wagon.

The caterpillar gun carriage is formed by two gun-carriage cheek beams 1 connected to one another in front and at the back by cross bars so as to form a longitudinal opening between the fore part and the rear. These beams are provided with lateral frameworks 2 provided with rollers 3

at their lower part. These rollers roll on chains 4 of the caterpillar type actuated by independent driving wheels 5 at the back and kept taut by the independent front wheels 6 which serve as chain stretching 60 wheels. The lateral frameworks may form a sliding path for the upper parts of the chains.

The motor system represented as actuating the driving wheels 5 consists of two receiving motors 7 connected with the driving wheels 5 by speed-reducing trains of gear wheels 8. 9 is the driving pinion, and 10 the axle of the driving wheels.

The electric current necessary for the receiving motors 7 is supplied by a generating set mounted on a wagon connected by a pivot-bolt to the rear of the caterpillar gun-carriage. The current supply cables are divided into two groups 12 and 13, one for 75 the right-hand motor and the other for the left-hand motor. They are inclosed in flexible tubes so as to be protected against any deterioration and to be able nevertheless to follow all the obliquities of the caterpillar 80 gun carriage with respect to the wagon carrying the generating set.

The two cheek beams of the gun-carriage 1 are furthermore united by two floors, below the front and the rear, in order to protect the internal mechanism, and by an upper floor 14 which supports at the back the receiving motors 7. This upper floor 14 is reinforced opposite to the driving wheels by a gun-carriage pivot carrying member 90 15, upon which the front of the carriage 21 rests and pivots about the pivot 16. The carriage is provided at the front with a circular claw 17 that engages the front portion of the pivot carrying member 15 in 95 order to relieve the pivot of the carriage of the recoil forces, as well as stanchions supporting the trunnions 18 of the cradle 19 of the gun. The fore part of the top carriage is formed of two cheeks 20 resting at their 100 ends on the upper floor 14. This top carriage 21 is provided with a gun-laying device operated by a screw 22 located laterally to the rear transom 23 of the top carriage and by the hand wheel 24 through the medium of bevel gearings and a connecting rod. This screw engages in a pivoting nut 25 mounted on the upper floor 14 in such a way that the nut can follow the traversing angles of the top carriage. The cradle 19 110

resting and oscillating between the cheeks 20 of the top carriage envelops a part of the rear of the gun. It incloses the recoil brake 26 the purpose of which is to limit the 5 recoil of the cannon and to insure its return to firing position and it guides the gun in its recoil movement. To one of the pivots 18 of the cradle 19 is fixed the toothed sector 27 for elevating the gun (Figs. 2 and 3) 10 operated by the worm and hand wheel 28 the function of which is to give the angle of aim to the gun. The guiding of the gun in the cradle during its sliding is effected by the rear part of the gun in the beginning 15 of the recoil and then by the front hoop.

The opening comprised between the gun-carriage cheeks permits of the movements of oscillation of the cradle and gun and the 20 recoil of the gun at the various angles of firing.

The caterpillar gun-carriage may be provided with trails and spades 29.

The movement that controls the laying 25 permits of the fine adjustments for firing. In order to effect a change of objective the caterpillar gun-carriage itself is actuated in such a way as to make it pivot about the rear of one of its chains in order to put it 30 into the new direction. That is to say, the whole caterpillar carriage may be moved for large changes of aiming.

The motor of the generating set which 35 has been assumed to be located on a trailer wagon, may be placed on the caterpillar gun-carriage itself, and may be an electric, hydrocarbon, steam or other motor.

The first alternative is illustrated in Figs. 4 and 5, in which the motor 30, for instance, 40 a hydrocarbon motor, placed on a trailer wagon 31 controls a dynamo 32 which feeds the electric motor 7 mounted on the carriage itself, while in Figs. 6 and 7 the motor 30 controlling the dynamo 32 is placed on the 45 carriage itself, together with the dynamo 32.

What I claim is:

1. A caterpillar gun carriage, comprising a chassis having a longitudinal central opening forming a gun-recoil space, 50 caterpillar chains on each side of the chassis, means for propelling each of the chains independently, a gun carriage pivotally mounted on the body of the chassis directly in front of said opening to oscillate laterally, means for oscillating the same, a gun cradle mounted pivotally on the carriage to oscillate within the opening of the chassis, and means for oscillating said cradle.

2. A caterpillar gun carriage, comprising 60 a chassis having a longitudinal central opening forming a space for a gun, caterpillar

chains on each side of the chassis to roll thereon, means for propelling each of the chains independently, a gun carriage mounted pivotally on the top floor of the chassis 65 directly in front of said opening to oscillate laterally, means controlling the oscillation of the carriage, a gun cradle pivotally mounted in the carriage to oscillate within the recoil opening of the chassis, and means 70 for controlling the oscillation of the cradle in the carriage.

3. A caterpillar gun carriage, comprising a chassis having a longitudinal central opening forming the recoil space for a gun, 75 front and rear chain wheels carried by the chassis, means for imparting independent motion to the rear chain wheels, a caterpillar chain on each side of the chassis from the rear wheel to the front wheel, rollers carried by the chassis and bearing on the chains, an axle for the rear chain wheels, a gun-carriage pivotally mounted to swing laterally on the chassis, said gun-carriage having means for engaging the chassis so as to relieve the pivot of the carriage from strain during the discharge of the gun, means for swinging the carriage on the chassis, a gun cradle pivotally mounted in the carriage to oscillate in the longitudinal opening of the 80 chassis, and means for oscillating the cradle in the carriage.

4. A caterpillar gun carriage, comprising a chassis having a longitudinal central opening forming the recoil space for a gun, 85 front and rear chain wheels carried by the chassis, a caterpillar chain on each side of the chassis from the rear wheel to the front wheel, rollers carried by the chassis and bearing on the chains, an axle for the rear chain wheels, a gun-carriage free to swing laterally on the chassis, said gun-carriage having means for engaging the chassis so as to prevent the carriage from moving longitudinally during the discharge of the gun, 90 means for controlling the swinging movement of the carriage on the chassis, a gun cradle pivotally mounted in the carriage to oscillate in the longitudinal opening of the chassis, and means for controlling the oscillatory movement of the cradle in the gun carriage, an electric motor for operating the front chain wheels, a motor controlling said 95 electric motor and placed on a trailer wagon.

In testimony whereof I have hereunto set 100 my hand at St. Étienne, France, this 20th day of June, 1917.

EMILE RIMAILHO.

In the presence of two witnesses:

JEAN BRUYERON,
DAVIS B. LEVIS.
